UNITED STATES PATENT OFFICE.

EDWARD S. STIMPSON, OF HOPEDALE, MASSACHUSETTS, ASSIGNOR TO DRAPER CORPORATION, OF HOPEDALE, MASSACHUSETTS, A CORPORATION OF MAINE.

FEELER MECHANISM FOR LOOMS.

Application filed March 26, 1924. Serial No. 701,838.

To all whom it may concern:

Be it known that I, EDWARD S. STIMPSON, a citizen of the United States, residing at Hopedale, in the county of Worcester and State of Massachusetts, have invented an Improvement in Feeler Mechanisms for Looms, of which the following description, in connection with the accompanying drawings, is a specification, like characters on the drawings representing like parts.

This invention relates to feeler mechanisms for looms whereby the operative condition of the loom is changed when the filling in the shuttle becomes substantially exhausted.

In that type of feeler mechanisms wherein the feeler is held in a frontward or inoperative position during periods of inactivity and is released from time to time to its period of activity during weaving with the same supply of filling in the shuttle, it is important that when the feeler is released to its periods of activity it shall move to full rearward feeling position, so that on a detecting beat the feeler may contact with the filling in its normal feeling position and perform its feeling function. Should the feeler be released to its period of activity on the advancing movement of the lay, it is liable to impact injuriously against the filling under the actuation of the means which moves the feeler to rearward position and the oncoming filling, and in such cases, also, the feeler is liable to jump and may call for a change of filling even when a working supply is present in the shuttle on a detecting beat. Under these conditions, also, the feeler is liable to move to its frontward position and there held by the holding means at a time when the feeler should remain in feeling position to detect the approach to substantial exhaustion of the filling.

The object of the present invention is to provide a feeler mechanism of the intermittent type which has periods of activity and inactivity during weaving with the same supply of filling in the shuttle, wherein mechanism is provided to insure that the feeler shall commence its feeling function on a period of activity in its full rearward position.

An important feature of the present invention, therefore, consists of an intermit-

tent feeler mechanism for looms, wherein the means for releasing the feeler to its periods of activity shall be rendered effective only when the shuttle is absent from the detecting box, so that the feeler is free to move to its full feeling position prior to the performance of its detecting function.

As now well known the crank-shaft of the loom and the under or cam shaft are actuated in a two to one relation and in accordance with the present invention this fact is utilized to actuate a train of mechanism which will insure that the feeler is released to the performance of its feeling function or periods of activity only on a non-detecting beat of the lay, or, in other words, when the shuttle is absent from the detecting box as the feeler moves to its feeling position.

The invention and new combination of parts will best be made clear from the following description and the accompanying drawings of one good practical form of the invention.

In the drawings:

Fig. 1 is a perspective view at the detecting side of the loom, showing the present invention associated therewith;

Fig. 2 is a sectional side elevation thereof; and

Fig. 3 is a perspective detail on larger scale showing features of the present invention.

The feeler mechanism of the present invention is shown as associated with means for effecting replenishment of filling when that in the active shuttle has become substantially exhausted, but the details of the replenishing mechanism are not shown because these may be of any usual type now well known. The invention is well demonstrated in association with any form of feeler mechanism, but in the present instance a feeler mechanism wherein the feeler is of the inclined type, is shown, it being understood that the invention is not restricted however to this particular form of feeler.

The loom frame 1 is of usual construction and has brackets 2, one at each side of the loom, for the support of the rock or transverse shaft 3 from which rises the arm 4 having pivoted thereto at 5 the rearwardly extending arm 6. To the arm 6 is pivoted

at 7 the member 8, the rear end portion of which is adapted at times to be engaged by the operating member 9, which may be formed as or connected to a part of the cam follower. The member 8 has a finger 10 which overlies the horizontal arm 11 of a bell crank lever pivoted at 12 on a support 13, and the other arm of the lever is connected at 14 to a transmitter 15 having its other end portion connected to a slide 16 mounted for transverse movement in the rear bearing portion 17 of the feeler stand 18. The feeler stand 18 is shown as secured to the loom frame by the bolt 19 by which it may be adjusted in position.

The feeler 20 extends through the rear bearing 17 and slide 16 and its frontwardly extending stem portion 21 passes through a swivel block 22. Between the swivel block 22 and the bridge or support 23 which is secured to the feeler is a spring 24 normally tending to move the feeler into its rearward feeling position. The parts so far described are shown as of the same construction and mode of operation as the similar parts in the patent to Edward S. Stimpson, No. 1,309,226, dated July 8, 1919, and when the feeler is moved longitudinally along the filling carrier it will, as set forth in said patent, call for a change of filling.

In the present invention the feeler is to be held in a frontward or inoperative position during its periods of inactivity, and is to be released at intervals to its periods of activity during weaving with the same supply of filling in the shuttle. In the present instance the feeler is provided with a tooth 25 which has an inclined rear surface adapted to be engaged by the inclined surface of a detent or catch 26, so that should the feeler be moved frontwardly by a working supply of filling on a detecting beat, the tooth 25 will pass frontward of the detent 26 and be engaged thereby to hold the feeler in its frontward inoperative position during its period of activity. When in its position of inactivity it is desirable that the feeler be held beyond the reach of the filling on a detecting beat, and this is accomplished in the present instance by making the engaging surfaces of the tooth 25 on the feeler and the detent 26 inclined as described, so that when the tooth 25 has engaged the detent 26 the inclined surfaces will cooperate under the impulse of the spring 24 to move the feeler a short distance laterally and consequently beyond the reach of the filling.

The detent 26 is pivoted at 27 on a bracket 28 adjustably secured to the feeler stand 18, as shown, and the bracket 28 may if desired be adjustably connected to the feeler stand and adjusted towards and from the front of the loom by an adjusting screw or device 29 in order to position the parts properly for the performance of their functions.

The lay 30 is of usual type and is provided with a detecting shuttle box 31, the front wall of which is provided with an opening 32 which registers with an opening 33 in the side wall of the shuttle 34 in which the filling carrier or bobbin 35 is mounted, the construction being such that on a detecting beat the feeler 20 may pass through the registering openings 32 and 33 when the shuttle is in the detecting box and perform its feeling function.

As shown more clearly in Fig. 2, the crank shaft 36 has mounted thereon the toothed wheel or gear 37 which is operatively engaged with the toothed wheel or pinion 38 secured to the lower or cam shaft 39, and the size of the toothed wheel is relatively such that the crank shaft makes two revolutions to each revolution of the under or cam shaft. The shuttle is picked by the picker stick 40 which, as usual in looms, receives its picking movements from a cam on the under or cam shaft 39, and in accordance with the present invention this timed relation of the shuttle picking movements from the under or cam shaft is utilized to actuate a train of mechanism to insure that the feeler shall be released to its feeling function or periods of activity only when the picking mechanism has been actuated to pick the shuttle from the detecting shuttle box, thus insuring that the feeler shall move to its full rearward position without obstruction and preferably on a non-detecting beat, so that its detecting function during its period of activity shall commence with the feeler in full rearward feeling position.

Operatively associated with the under or cam shaft 39 is a reach shaft 41 which may be rotated from the under or cam shaft by the enmeshing beveled gears 42, 43, Fig. 2. In the present instance the reach shaft 41 is supported in suitable bearings 44, 45 secured to the loom frame, the construction being such that on each rotation of the under or cam shaft 39 the reach shaft 41 will be rotated.

In the present instance of the invention the reach shaft 41 is shown as the shaft for actuating the take-up mechanism of the loom, comprising a train of gears 46, 47, 48, 49 and 50, Fig. 1, but since the take-up mechanism forms no part of the present invention, further details thereof are not shown or described, the essential being that the reach shaft 41 shall receive its rotative movement from the under or cam shaft 39, which, as hereinbefore described, actuates the picking mechanism.

Mounted on the reach shaft 41 is a cam 51 which may be conveniently formed in two parts, as shown, Fig. 1, and clamped to the reach shaft by the clamp 52. This is a convenient manner of associating the cam 51

upon the reach shaft which in many looms constitutes or may constitute the actuating means for the take-up.

Mounted for rocking movement in the bearing 53 is the rock shaft 54 having a portion 55 which bears upon the inclined surface of the cam 51, and consequently as the cam is rotated the rock shaft 54 is given a rocking movement. The bearing 53 may be secured to the loom in any appropriate manner, but is herein shown as carried by a rod 56 secured to the shipper stand 57 at 58, and the lower end of the rod 56 supports the bearing 53, in the present instance, by a clamp 59 which serves to hold the bearing 53 in position with the arm 55 of the rock shaft 54 engaged with the cam 51. Obviously, the details for mounting the rock shaft 54 in the bearing 53 may be varied 10 within wide limits, the essential being that the rock shaft 54 shall be supported for rocking movement by the cam 51 on the reach shaft. The rock shaft 54 in the present instance has secured thereto an arm 60 which, in the present instance, is clamped to the rock shaft by the bolt 61. The arm 60 has a pin 62 on which is mounted the lower end portion of an arm for actuating the detent release. In the present instance, 15 this arm is formed by a part 63 mounted on the pin 62 for rocking movement and clamped to the part 63 is the upwardly extending rod 64.

The upper end portion of the rod 64 carries a pawl member 65 which is guided in its reciprocating movements in a casing 66 secured to the feeler stand. Mounted on the shaft 67 projecting from the feeler stand is the ratchet wheel 68, the teeth 69 of which are engaged by the actuating pawl 65, so that on reciprocating movement of the pawl the ratchet wheel will be stepped along tooth by tooth. The casing 66 in which is guided the pawl 65 may appropriately be 20 formed as a shield for the ratchet wheel, as shown.

Extending from the detent 26 is a lug 70 and the active end of the detent is normally held in its lower position by means of a light spring 71 interposed between the front end of the detent 26 and the bracket 28, as indicated in Fig. 3. The ratchet wheel 68 has secured thereto a trip 72 which, as the ratchet wheel is stepped along by the train of mechanism described and actuated from the under or cam shaft 39 finally rises beneath the lug 70 and lifts the detent 26 to free the feeler to its periods of activity.

The ratchet wheel 68 is stepped along by 25 the train of mechanism actuated from the under or cam shaft 39, from which the picking movement of the shuttle is imported, and the relation of parts is such that the trip 72 will engage and lift the detent to free the feeler to its periods of activity only

when the shuttle has been picked from the detecting shuttle box, thus insuring that when the feeler is released to its periods of activity, it will move to its full feeling position when the shuttle is absent from the detecting box or the lay is making its non-detecting beat.

Assuming that the feeler is in its rearward feeling position, as indicated in Fig. 1, and the lay is making a detecting beat, the 75 feeler will be moved forwardly by the filling, provided a working supply of filling is in the shuttle and the rear end portion of the detent will be lifted to permit the tooth 25 of the feeler to move forwardly thereof, 80 whereupon the detent will drop under the actuation of the spring 21 and hold the feeler in its forward or inactive position. As the ratchet wheel 68 is stepped along in timed relation with the under or cam shaft, 85 and consequently with the picking mechanism, the trip 72 will finally rise beneath the projecton 70 on the detent and free the feeler for movement to its full feeling position on a non-detecting beat of the lay or 90 when the shuttle is absent from the detecting box, so that on the next detecting beat the feeler will be in full feeling position to perform its feeling function, and should it at such time detect a close approach to substantial exhaustion, the feeler will not be moved forwardly sufficiently far to be engaged by the detent but will remain in an active position until when the filling is substantially exhausted, it will call for a change 95 of filling.

Applicant believes himself to be the first in the art of intermittent feeler mechanisms to provide a feeler release which will insure that the feeler may move to its full feeling 100 position when the shuttle is absent from the detecting box or when the lay is making its non-detecting beat, which is the main purpose and intent of the invention.

What is claimed is:

1. In an intermittent feeler mechanism for looms, the combination of a feeler, means for holding the feeler in retracted position beyond the reach of the filling on detecting beats during periods of inactivity and freeing it at intervals to periods of activity during weaving with the same supply of filling in the shuttle, and mechanism timed with relation to the picking movements of the shuttle for causing release of the feeler to its periods of activity only when the shuttle is absent from the detecting shuttle box.

2. In an intermittent feeler mechanism for looms, the combination of a feeler, a detent for holding the feeler in its inoperative position during its periods of inactivity, picking mechanism for the shuttle, a cam, a shaft on which the cam is mounted, and means actuated by the cam in timed rela-

tion with the picking mechanism to insure that the feeler may move to its feeling position after the shuttle has been picked from the detecting shuttle box and prior to its return thereto.

3. In an intermittent feeler mechanism for looms, the combination of a feeler, feeler controlling means for holding the feeler in an inoperative position for periods of in-

10 activity and freeing it at intervals to its periods of activity, and means actuated from the under or cam shaft for freeing the feeler from its controlling means only when the shuttle is absent from the detecting shuttle box that the feeler may assume its rear-

15 ward feeling position to detect the condition of the filling on the following detecting beat.

4. In a feeler mechanism for looms, the combination of a feeler, a catch for holding the feeler in a frontward position beyond the reach of the filling on detecting beats, a trip for freeing the feeler from the catch at intervals that the feeler may have periods of activity and inactivity during weaving

20 with the same supply of filling in the shuttle, and means for causing the trip to release the feeler only when the shuttle is absent from the detecting shuttle box to insure that the feeler will communicate its periods of activ-

25 ity in full feeling position.

5. In a feeler mechanism for looms, the combination of a feeler, a catch for holding the feeler in an inactive position, beyond the reach of the filling on detecting beats and a cam actuated in timed relation with the shuttle picking movements to free the feeler at intervals to its periods of activity during weaving to insure that the feeler be in rear-

30 ward feeling position when it enters the shuttle to detect the condition of the filling.

6. In a feeler mechanism for looms, the combination of a feeler, a catch for holding the feeler in an inactive position, and a cam actuated in timed relation with the shuttle

35 picking movements and a train of mechanism operated by the cam to free the feeler at intervals to its periods of activity during weaving to insure that the feeler be in rear-

40 ward feeling position when it enters the shuttle to detect the condition of the filling.

7. In an intermittent feeler mechanism for looms, the combination of a feeler, a spring normally tending to move the feeler rearwardly to feeling position, means for

55 holding the feeler in an inoperative position in opposition to said spring and for freeing the feeler at intervals that it may have periods of activity and inactivity during weaving with the same supply of filling in the shuttle, and means including a cam 60 actuated from the under shaft for freeing the feeler to its periods of activity only when the shuttle is absent from the detecting shuttle box.

8. In an intermittent feeler mechanism for looms, the combination of a feeler, a 65 detent for holding the feeler in a frontward inoperative position beyond the reach of the filling, a trip for freeing the feeler from the detent at intervals that the feeler may have 70 periods of activity and inactivity during weaving with the same supply of filling in the shuttle, and means operating in timed relation with the picking movements of the shuttle for causing the trip to release the 75 feeler to its periods of activity only when the shuttle is absent from the detecting box.

9. In an intermittent feeler mechanism for looms, the combination of a feeler, a 80 detent for holding the feeler in a frontward inoperative position, a trip for freeing the feeler from the detent at intervals that the feeler may have periods of activity and inactivity during weaving with the same supply of filling in the shuttle, the under or cam 85 shaft, a reach shaft actuated thereby, and a cam on the reach shaft for freeing the feeler from the detent when the shuttle is absent from the detecting shuttle box, and means operating in timed relation with the 90 picking movements of the shuttle for causing the trip to release the feeler to its periods of activity only when the shuttle is absent from the detecting box.

10. In an intermittent feeler mechanism 95 for looms, the combination of a feeler, means for holding the feeler in frontward retracted position beyond the reach of the filling during periods of inactivity and freeing it at intervals to periods of activity during weaving with the same supply of filling in the shuttle, and means for freeing the feeler for movement to feeling position only on a non- 100 detecting beat of the lay.

In testimony whereof, I have signed my 105 name to this specification.

EDWARD S. STIMPSON
